UNITED STATES PATENT OFFICE.

WALTER EDWIN FROST, OF AUBURN, MAINE, ASSIGNOR OF ONE-HALF TO HOLMAN GOULD, OF AUBURN, MAINE, AND ONE-FOURTH TO JOHN B. SMITH, OF LESTON, MAINE.

DAMPER FOR FURNACES.

1,202,700.

Specification of Letters Patent.

Patented Oct. 24, 1916.

Application filed February 10, 1916. Serial No. 77,491.

To all whom it may concern:

Be it known that I, WALTER E. FROST, a citizen of the United States, residing at Auburn, in the county of Androscoggin and State of Maine, have invented certain new and useful Improvements in Dampers for Furnaces; and I do declare the following to be a full, clear, and exact description of the invention, such as will enable others skilled in the art to which it appertains to make and use the same.

This invention has reference to certain improvements in furnace dampers of the type intended for use in the flues leading from the furnace to the chimney.

More particularly, the invention has reference to certain improvements in dampers of the foregoing type, and which are intended to permit the entrance of fresh air into the flue, which fresh air flows by a counter-current movement back through the flue into the furnace. Admission of the fresh air into the furnace in this manner serves to supply the necessary oxygen for carrying on the combustion within the furnace at the ordinary or normal rate or intensity, without the necessity of leaving the furnace or ash pit doors open during the normal operation.

The main object of the invention is to provide a damper of peculiar construction such that incoming air is caused to pass through the body of the damper to be thereby heated by the waste heat which is going up the flue. In this manner, a considerable portion of the waste heat is conserved so that the efficiency or economy of the furnace is greatly improved. At the same time the pre-heating of the air permits the attainment of a higher temperature of combustion than would otherwise be possible.

Another object of the invention is to so construct the damper that it can be readily inserted into the flue without the necessity of specially constructing the flue, and without the necessity of cutting or opening the flue other than the forming of a pair of oppositely disposed holes in the flue.

A still further object of the invention is to provide a device of this character in which the flow of air is regulated by a valve.

Other objects and uses will appear from a detailed description of the invention which

consists in the features of construction and combinations of parts hereinafter described and claimed.

In the accompanying drawings in which similar reference characters designate like parts throughout the several views, Figure 1 is a side elevation of a damper constructed in accordance with this invention, showing it applied to a smoke pipe, the same being shown in section; Fig. 2 is a horizontal sectional view taken on the plane of the line 2—2 of Fig. 1; Fig. 3 is a similar view showing the cover plate removed; Fig. 4 is a vertical sectional view taken on the plane of the line 4—4 of Figs. 2 and 3; Fig. 5 is a similar view taken on the plane of the line 5—5 of Figs. 2 and 3; Fig. 6 is a modified form of the invention showing the same applied to the smoke pipe, the same being shown in section; and Fig. 7 is a horizontal section taken on the plane of the line 7—7 of Fig. 6.

Referring more particularly to the drawings, the numeral 1 designates the flue or smoke pipe leading from a furnace or boiler to the chimney, and arranged within this pipe 1 is a damper 2 to which the present invention relates. As previously stated, it has been found by experience that fresh air may be admitted into the flue at a point close up to the furnace, and such air will drop back into the furnace to supply the necessary oxygen for combustion without the necessity of opening the furnace or ash pit doors.

The form of damper shown in Figs. 1 to 5 of the drawings comprises a casting 3 composed of a metal plate 4 having an annular flange 5 extending laterally from the peripheral edge thereof, and a centrally arranged opening 6, from the edges of which extends a second annular flange 7. Disposed in a tortuous path between the two flanges 5 and 7, is a partition 8, thereby forming an irregular or tortuous channel 8' for the passage of air therethrough. Fixed in any suitable manner, here shown by bolts 9, to the open side of the casting 3 and tightly contacting with the edges of the flanges 5 and 7 and the partition 8, is a circular cover plate 10 which is provided with a central opening 11. Threaded or otherwise secured in a suitable opening in the cover plate 10 adjacent the central opening 11 thereof and

in communication with the channel or passage 8', is a tubular air outlet pipe or nipple 12.

The numeral 13 represents a threaded opening arranged in the flange 5 adjacent the outer or inlet end of the air passage 8', and threaded in this opening 13 is a tubular nipple 14 having its outer end shaped to form a suitable valve seat, for a purpose to be described. Arranged similarly on the diametrically opposite side of the casting 3 is a closed nipple or stud 15. These two nipples 14 and 15 act in the capacity of trunnions for pivoting the damper in suitable openings 16 arranged in the opposite walls of the smoke pipe 1. Surrounding the nipple or stud 15 and disposed between the outer side of the pipe 1 and the inner side of a collar 17, is a coiled spring 18, which, as will be readily understood, prevents the damper from becoming accidentally displaced. A similar collar 19 is arranged on the nipple 14.

Threaded on the outer end of the nipple 25 14 is a triangular-shaped handle having a hub portion 20, from the outer end of which extends substantially longitudinally of said nipple 14 a pair of spaced arms 21, the latter being integrally connected at 30 their outer ends by a strap or cross bar 22. This cross bar 22 is provided with a threaded aperture 23 arranged in alignment with the open outer end of the nipple 14, and operating in the aperture 23, is a screw 24, the inner end of which is cone-shaped and adapted to be disposed in the valve seat in the outer open end of the nipple 14, for regulating the admission of and flow of air through said nipple 40 and the passage through said damper. This handle is arranged in the same general plane with the damper so that the general position and amount of opening or inclination of the latter may be determined by the 45 relative angle of the handle to the pipe 1, as will be readily understood without further description.

In Figs. 6 and 7 of the drawings, the damper 2 is composed of a plurality of 50 closely arranged parallel pipes 25, the ends of the adjacent ones being connected by U couplings 26 as shown, thereby forming a continuous flat coil through which air may pass. Threaded to suitable T couplings 27 55 arranged substantially midway between the ends of the pipes at the opposite edges of the coil, are the aforesaid trunnions 14 and 15, by which the coil is pivotally mounted in the pipe 1. Extending inwardly from the open end of the pipe 25 to which the trunnion 15 is connected, is an air outlet pipe 28, while the free end of the pipe 25 to which the trunnion 14 is fastened, is closed by a suitable cap 29. As shown, the U 60 couplings 26 are arranged in staggered re-

lation in order to allow the pipes 25 to be arranged closely together.

By this arrangement of parts, fresh air from the outside will pass through the nipple 14, the amount, however, being regulated by the conical valve 24. From the nipple 14 the air will pass through the air passage or channel 8' in the form of damper shown in Figs. 1 to 5 of the drawings to the interior of the pipe 1. During this tortuous passage it will be heated by the hot smoke and gas passing through the pipe 1 around the damper 2 and the central opening 6, thus more effectively combining with the combustible gases, as will be readily understood. In Figs. 6 and 7 it will pass through the coil.

From the foregoing description, taken in connection with the accompanying drawings, the operation of the invention will be understood without a more extended explanation.

While I have herein shown and described only two forms of construction embodying features of my invention, still it will be understood that I am in nowise restricted to these forms, except as may be called for in the claims, but that I include within the scope of my invention other equivalent arrangements operating in equivalent manners to produce equivalent results.

I claim:

1. A device of the class described comprising a damper having an air passage therethrough, trunnions extending outwardly from the opposite edges of said damper, one of said trunnions having an air passage therethrough communicating with the passage through said damper, a pair of spaced arms secured to the outer end of the last mentioned trunnion and extending substantially longitudinally of the same, a cross bar connecting the outer ends of said arms and having a threaded aperture therein, and a screw operating in said aperture and having its inner end disposed in the open end of the last mentioned trunnion for regulating the flow of air through said passages.

2. A damper of the class described comprising a flat closely formed continuous coil of pipes, trunnions extending outwardly from the opposite edges of said coil, one of said trunnions having an air passage therethrough in communication with a portion of said coil, a pair of spaced arms secured to the outer end of the last mentioned trunnion and extending substantially longitudinally of the same, a cross bar connecting the outer ends of said arms and having a threaded aperture therein disposed in alignment with the outer end of said passage, and a screw operating in said aperture, the inner end of said screw being provided with a conical valve for regulating the flow of air through said passage and said coil.

3. A damper of the class described comprising a plurality of closely arranged parallel pipes, **U** couplings connecting the ends of adjacent pipes to form a flat continuous coil, trunnions extending outwardly from the opposite edges of said coil, one of said trunnions having an air passage therethrough in communication with a portion of said coil, a pair of spaced arms secured to the outer end of the last mentioned trunnion and extending substantially longitudinally of the same, a cross bar connecting the outer ends of said arms and having a threaded aperture therein disposed in alignment with the outer end of said passage, and a screw operating in said aperture, the inner end of said screw being provided with a conical valve for regulating the flow of air through said passage and said coil.
- 10 4. A damper of the class described comprising a plurality of closely arranged parallel pipes, **U** couplings connecting the ends of adjacent pipes to form a continuous flat coil, a trunnion extending outwardly from the pipe at one of the edges of said coil, a tubular nipple secured to the pipe on the opposite edge of said coil and communicating with the interior thereof, a pair of spaced arms secured to the outer end of said nipple and extending substantially longitudinally of the same, a cross bar connecting the outer ends of said arms and having a threaded aperture therein disposed in alignment with the outer end of said passage, and a screw operating in said aperture, the inner end of said screw being provided with a conical valve for regulating the flow of air through said passage and said coil.
- 15
- 20
- 25
- 30

ment with the open end of said nipple, and a screw operating in said aperture and having a cone-shaped inner end disposed in the open end of said nipple, whereby to form a valve for regulating the flow of air through said nipple and said coil.

5. A device of the class described comprising a damper having trunnions extending outwardly from its opposite edges, one of said trunnions being provided with a valve seat at its outer end, a triangular-shaped handle having a hub portion fixed to the outer end of the last mentioned trunnion, and a screw adjustably mounted on the cross bar of said handle and having its inner end disposed in said seat.

6. A damper of the class described comprising a plurality of closely arranged parallel pipes, **U**-couplings connecting the ends of adjacent pipes to form a continuous flat coil, **T**-couplings arranged in the outermost plates, trunnions secured to said **T**-couplings, one of said trunnions communicating with the interior of said coil and having a valve seat therein, and a valve disposed in said seat.

In testimony whereof I have hereunto set my hand in presence of two subscribing witnesses.

WALTER EDWIN FROST.
